UNITED STATES PATENT OFFICE.

FERDINAND G. HAAS, OF SPRINGFIELD, MISSOURI.

BOILER FLUE, PIPE, AND TUBE CUTTING MACHINE.

No. 839,135.

Specification of Letters Patent.

Patented Dec. 25, 1906.

Application filed April 7, 1906. Serial No. 310,521.

To all whom it may concern:

Be it known that I, FERDINAND G. HAAS, a citizen of the United States, residing at No. 520 New street, Springfield, State of Missouri, have invented a new and useful Boiler Flue, Pipe, and Tube Cutting Machine, of which the following is a specification.

My invention relates to an entirely new kind of boiler flue, pipe, and tube cutting machine in which by means of two eccentrics, one inside the other and operated by a rod and a hand-wheel, I can place a large circular cutter inside the flue to be cut.

The object of this machine is to do away with so many delicate springs and small screws, small cutters, air-pistons, wedges, cams, and gears now in use and to produce a more substantial machine which costs less to make and keep in repair and which one man can operate with ease. I obtain these objects by the mechanism illustrated in the accompanying drawings, in which—

Figure 1 is a horizontal section view of the entire machine. Figs. 2 and 3 are detail views.

Similar letters refer to similar parts throughout the several views.

A is the cutter, which revolves on and is held in place by the stud-bolt B and screwed 30 into the adjusting-eccentric E.

E is an adjusting-eccentric which is fitted into the equalizing-eccentric D.

C is the shell that enters the boiler flue, pipe, or tube up to the shoulder S and acts as 35 a bearing for D to revolve in.

I is a tube or pipe one end of which screws into an equalizing-eccentric D and the other end is cut, as shown in Fig. 2, to allow the one spoked hand-wheel M to make half a turn, 40 which brings the cutter in contact with the boiler flue, pipe, or tube.

F is a rod one end of which is screwed into the eccentric E, with a shoulder E² to keep E from slipping backward and a shoulder F² on rod F to keep it from slipping forward, and the two hold the same in place, and the other end J is squared to enter the square J J in hand-wheel M, Fig. 2, and a small guide G, that enters the eccentric-bushing X, which 45 is made to correspond with eccentric E, holds the rod F and hand-wheel M rigid and in line with eccentric E.

R represents ball-bearings to reduce friction.

V is a spring-ring sprung over C and D and enters the grooves W, provided for same, and

to prevent dust and grit from getting into the bearing, and also to keep C and D together.

X is an eccentric-bushing one end of which enters into the tube or pipe I and is fastened to same by pin P and is cut out at the back same as pipe or tube II in Fig. 2 to allow hand-wheel to enter.

O is a ratchet, a part of eccentric-bushing X, which extends half-way around the said eccentric-bushing X, into which the pawl L fits to keep the cutter A in the desired position while cutting and is fastened to the single spoke of the hand-wheel M by the pin N and kept in mesh by the spring Y, fastened 70 in or to the hand-wheel M.

XX is a square on the eccentric-bushing X to fit a wrench when worked by hand.

T is a taper shank of standard size to fit any motor to run the machine by power. Fig. 3 shows the eccentric D. Fig. 2 shows 75 the hand-wheel.

K K are webs to strengthen hand-wheel.

JJ represent the square into which the square J on rod F fits.

LL in Fig. 2 is where the pawl L, Fig. 1, fits in.

Z is a thumb-plate on the pawl L, by pressing which draws the pawl L out of mesh and allows the cutter to be set at a starting-point, as shown by dotted line of A², Fig. 1. The machine is set at starting-point, as indicated by dotted lines A² in Fig. 1, and enters into the boiler flue, pipe, or tube up to shoulder S on shell C. Then machine is run 90 or propelled either by hand or power attached to the square XX or taper or shank T. The cut in the flue or tube is regulated by the hand-wheel M, aided by the teeth in the ratchet, or the wheel M may be 95 provided with a friction or other means of regulating the cut, and at the same time the power attached to the taper or shank T revolves the cutter in the flue or tube to be cut off.

Having thus described my invention, what I claim as new, and desire to secure by Letters Patent of the United States, is—

1. In a flue-cutting machine, a combination of a circular cutter carried by an eccentric for adjusting the cutting by means of a rod and a one-spoked adjusting-wheel, said eccentric carried by another equalizing-eccentric for enabling the circular cutter to enter the flue to be cut, said eccentric being driven 105 by a tube connected with a driving-shank and an eccentric-bushing carrying the ad-

- 2 justing-rod, all substantially as shown and described.
2. In a flue-cutting machine, the combination of a circular cutter carried by an adjusting-eccentric said eccentric carried by an equalizing-eccentric, a containing-sleeve having ball-bearings for a shoulder of the equalizing-eccentric, and a spring-ring for protecting the joint and holding the equalizing-eccentric to said sleeve. 35
3. In a flue-cutting machine, the combination of an eccentric carrying a cutter, said eccentric being carried by another eccentric for permitting the cutter to enter the flue, a sleeve for receiving the latter eccentric, said sleeve provided with a shoulder for holding the machine in position, and a driving-tube, rod, and eccentric-bushing, all substantially as and for the purpose specified. 40
4. In a flue-cutting machine, the combination of a cutter secured to an eccentric for adjusting the position of the cutter said eccentric carried by an eccentric for offsetting the eccentric which carries the cutter to enable the cutter to enter the flue to be cut, a receiving-sleeve for holding the eccentrics in position in the flue said sleeve having a shoulder for adjusting its depth in the flue and the eccentric being carried by bearings on the outer end of the sleeve, said eccentric being operated by a tube and an eccentric- 45
- bushing having a shank for power attachment a rod all substantially as shown and described. 50
5. In a flue-cutting machine, an adjusting-eccentric provided with shoulders for holding the same to and in an equalizing-eccentric within a flue, said equalizing-eccentric having shoulders for forming bearings on a containing-sleeve and an eccentric-bushing on the back end for driving the cutter substantially as specified. 55
6. In a flue-cutting machine, an eccentric for carrying and adjusting a cutter combined with an equalizing-eccentric which enables a large cutter to enter the flue connected with an equalizing eccentric-bushing at the back end for keeping the machine on a line while being driven, substantially as shown and described. 60
7. In a flue-cutting machine, an eccentric-bushing cut one-half away combined with a single-spoke adjusting-wheel and a driving-shank for operating the machine, combined with a double eccentric which enters the flue and an eccentric-bushing for driving the machine, as specified. 65

FERDINAND G. HAAS.
